UNITED STATES PATENT OFFICE.

THOMAS KOLINGER AND LOUIS HABUNEK, OF MARTINS FERRY, OHIO.

AUTOMATIC COUPLER FOR MINERS' CARS.

Application filed January 13, 1926. Serial No. 80,879.

This invention relates to cars used in mines, the invention having more particular reference to a novel type of coupling for cars used in mines.

5 The invention has for an object the provision of a coupler, which is self operating, and of simple, reliable construction.

For further comprehension of the invention, and of the objects and advantages 10 thereof, reference will be had to the following description and accompanying drawing, and to the appended claims in which the various novel features of the invention are more particularly set forth.

15 Fig. 1 of the drawing, is a top plan view of a car, such as used in mines, showing my improved coupler attached thereto.

Fig. 2 is a central, side sectional view showing two cars attached by means of my 20 improved device.

Fig. 3 is an end elevational view, of a car equipped with my improved coupler.

Fig. 4 is a similar view.

In the accompanying drawing, we have illustrated cars such as ordinarily used for mining purposes, having flanged wheels 10, rotatably attached to the truck 11, which supports a body 12, having sides 13 and ends 14, one of the ends being hinged to the 25 sides, as designated by the numeral 15, by supporting members 16. The hereinbefore mentioned construction being in general, common to cars of this nature and type, it will be understood that we do not confine our 30 invention to this particular type of mining car, but to mining cars of all classes and description.

As here embodied our improved coupler comprises two members 17 and 18. The 40 member 17, has a lower portion 17' conveniently located aperture 19 to accommodate the U shaped supporting bar 20, which is attached to the car by a pin 22, it being understood that the member 17 is swingably 45 attached to the supporting bar 20, and has an elongated aperture 23 extended therefrom, by the extension 23' and a suitable support 24 for the counter-weight 25, which is slidably attached thereto by means of a 50 screw 26, or any similar suitable means.

The member 18 has an aperture located at or near one of its extremities to accommodate the pin 27, as a means of attaching the 55 said member 18 to the car, and is also provided with an extended portion 28, and an upright hook shaped piece 29, either integral

with the member 18, or attached thereto. The spring 30 having a semi-circular portion 31 at one of its extremities, is suitably attached to the member 18 as at 32, and is so 60 positioned that the semi-circular portion 31 is pressed against the inner side of the hook shaped piece 29.

As a means of attaching the member 17 and 18 to the supporting bar 20, and to the 65 pin 27, respectively, we have provided a block, 32, having a semi-circular aperture 33 and a stepped surface 34 fitting in the groove 35 suitably located in the member 17 and 18, the said block 32 being attached thereto by a 70 bolt 36, or any similar screw or fastening device. We have also provided a hook 38 pivoted as at 39, which may be engaged with the extended extremity 40 of the coil spring 41, as a safety coupling device. 75

The functioning or operation of our improved coupler for mining cars is as follows, the member 18 is so positioned that its extended portion 28 will strike the lower portion 17' of the member 17, when the two cars 80 equipped with my improved device are backed or otherwise forced toward one another, which will cause the said member 17 to swing on the support 24, the elongated aperture 23 will thereby be swung outwardly 85 and will strike the spring 30, forward of the hook shaped piece 29, and will force the spring 30 downward momentarily, which will permit the extension 23' to engage in the semi-circular portion 31, which will couple 90 or attach the two cars. It being understood that the counter-weight 25 is so positioned on the support 24, preferably as designated by the number 37, so as to assure the action 95 as described above, it being obvious that the said counter-weight 25 is so positioned as to normally hold the member 17 in an upright position.

While we have above described the preferred form, construction and arrangement 100 of the several elements employed, it will be understood that the device is, nevertheless, susceptible of considerable modification therein, and we therefore reserve the privilege of resorting to all such changes as may 105 be fairly embodied within the spirit and scope of the invention as claimed.

Having thus described our invention, what we claim as new and desire to protect by Letters Patent of the United States is as follows: 110

1. A coupler for mining cars comprising

a self operating means of coupling said cars, and an adjustable counter balance for returning said coupler to an uncoupled position.

2. A coupler, self operating, for mining cars comprising two members, so positioned that one member will strike the other member, when the said cars are forced toward one another, and a resilient member positioned to receive one of said members and force it into locked engagement with the other member, which will cause the first mentioned member to engage with the second mentioned member.

3. A coupler, self operating, for mining cars comprising two members, so positioned that the extended portion of one member will strike the lower portion of the other member, when the said cars are forced toward one another, which will cause the first mentioned member to swing on a support, an elongated

aperture located therein will be swung outwardly and will permit an extension to engage with the second mentioned member.

4. A coupler for mine cars, comprising a loop member swingably attached to one of said cars, a hook member secured to the adjacent end of another car, means extending from said last mentioned car in position to register with one end of said loop member and adapted to strike and swing the latter towards said hook member, a spring secured at one end and formed at the other to conform with the curvature of said loop member for receiving and moving the latter into locked engagement with said hook member.

In testimony whereof we have affixed our signatures.

THOMAS KOLINGER.
LOUIS HABUNEK.
